UNITED STATES PATENT OFFICE

WILLIAM F. CONRAN, OF BROOKLYN, NEW YORK

STANDPIPE SYSTEM

Application filed May 8, 1928. Serial No. 276,063.

This invention relates to fire extinguishing standpipes of the general type disclosed in United States Patents Nos. 816,152 and 1,253,005, granted to me March 27, 1906, and January 8, 1918, respectively, and consists broadly in the provision of a new and improved form of this type of apparatus, in which the control thereof is facilitated and information concerning operating conditions at the standpipe discharge nozzles is given to the standpipe operator at a point remote from the nozzles.

For a better understanding of the invention, its more specific objects and the advantages accruing from the use of one or more of its several features, reference may be had to the accompanying drawings forming a part hereof and to the following detailed description of the apparatus illustrated, by which the invention may be carried into effect.

In the drawings:

Fig. 1 is a fragmentary elevation of a standpipe embodying the invention;

Fig. 2 is a section taken on the line 2—2 of Fig. 1;

Figs. 3 and 4 are enlarged sectional views of portions of the standpipe;

Figs. 5 and 5^a are, respectively, front and side elevations, on an enlarged scale, of a rest used with the standpipe;

Figs. 6 and 6^a are, respectively, enlarged elevation and bottom plan views of one form of control bracket to be used with the standpipe;

Figs. 7, 7^a and 7^b are, respectively, plan and front and side elevations of another form of control bracket;

Figs. 8 and 8^a are, respectively, a plan and elevation of a third form of control bracket;

Fig. 9 is an elevation (greatly enlarged) of a gauge used with the standpipe;

Fig. 10 is a side elevation, partly in section, of the gauge illustrated in Fig. 9;

Fig. 11 is an enlarged elevation, partly in section, of a nozzle fitting assembly and valve; and

Fig. 12 is a section taken on the line 12—12 of Fig. 11.

Referring now to Fig. 1, the standpipe is shown as comprising a plurality of pipe sec-

tions connected by nozzle carrying fittings 2 and a control fitting 3. For purposes of illustration the standpipe is shown rotatably mounted within a building, the pipe sections extending through the floors 4 thereof and receiving lateral support from the bearing sleeves 5 set in the floors. Rotation of the standpipe is accomplished by means of a manually operable lever, preferably located adjacent to the control fitting 3. It is to be understood, however, that the invention is not limited to a standpipe located in this manner, but may be applied as well to a standpipe located exteriorly of any building or other similar structure it is designed to protect. Further, it will be clear that while only the lower portion of the standpipe is illustrated, the height thereof and the number of nozzles carried is greater than that shown and will vary with the height of the structure to be protected.

The lowermost pipe section 1 extends through the cover plate 6 of a base cylinder 7 and has secured to its lower end a piston 8 provided with suitable packing 9. The cover plate 6 carries a circular flange 10, forming, with the pipe 1, a ball race retaining a plurality of bearing balls facilitating the movement of the pipe in and out of the cylinder and also rotation with respect thereto.

The control fitting 3, located at the point selected as the operating station is provided with a Siamese inlet connection 11, serving to admit the fire extinguishing fluid, ordinarily water under pressure, to the standpipe. It also is provided with a pair of openings having stuffing-boxes 12 through which the control pipe 13 passes from the interior of the standpipe to the exterior thereof and again to the interior. The upper end of pipe 13 is open, as indicated in Fig. 3, and the pipe extends downwardly through the standpipe and communicates with the cylinder 7 below the piston 8 through the orifices 14 in the latter. A three-way valve 15 is mounted in the section of pipe 13 outside the standpipe, this valve being provided with a manually operable handle 16 arranged so that when it is in the position shown in Fig. 3 the pipe 13 is open to place the lower end

of cylinder 7 in communication with the interior of the standpipe. In this position of the valve, the standpipe is lifted by the pressure of the fluid admitted from the standpipe to the lower side of piston 8. When the valve handle 16 is moved to a horizontal position, the valve 15 is closed and the standpipe is held at the level attained by the fluid trapped below the piston. When the handle 16 is moved below the horizontal position, the valve 15 vents the cylinder 7 to the atmosphere or a suitable drain through port 17, in which event gravity acts to lower the standpipe. Obviously, the valve 15 travels with the standpipe, and in order to provide control over it at various levels, it has attached thereto the operating chain or cable 18.

As the standpipe forms a structure of comparatively great weight and in some instances may be subject to binding because of misalignment, the piston 8 must be of sufficient area to exert a powerful force. Furthermore, movement of the standpipe creates relatively large inertia forces, and it will readily be apparent that if through inadvertence on the part of the operator, or through any other cause, the standpipe is set in upward motion by manipulation of valve 15, and the latter is not closed before some element of the standpipe strikes a limiting abutment, such, for example, as the piston 8 striking the cover of cylinder 7, or the fitting 3 striking a floor 4, serious, and probably damaging, shock to the apparatus will be the result.

In order to prevent such a contingency, an automatic stop or control bracket is provided, adapted to engage the valve handle 16, in any position of rotation of the standpipe, when the latter reaches a predetermined height. As shown in Figs. 1, 6 and 6^a, this bracket takes the form of a ring 19 to which are attached a plurality of perforated hanger strips 20. A like number of arms 21 are mounted to depend from the floor above the control fitting and around the standpipe. To these arms the strips 20 are bolted, with ring 19 encircling the standpipe at a height determined by the selection of the hole through which the strips 20 are bolted. The operation of the stop is largely obvious. As the standpipe rises to the limiting position, the valve handle 16 strikes ring 19 and is moved toward a horizontal position from its necessarily upwardly angular position. When the valve is moved to closed position (with the handle horizontal), motion of the standpipe ceases, because of the non-expanding nature of the fluid in cylinder 7, and return of the standpipe to a lower position is effected by manually moving the valve to release or venting position through the medium of the chain 18.

If automatic return of the standpipe is desired, a spring, or its equivalent, may be

provided to pull the handle 16 downward to release position after it has been moved to a neutral or closed position by the ring 19.

In Figs. 7, 7^a and 7^b another form of stop bracket is illustrated. This form is particularly adapted to be mounted to a vertical wall, but may by the use of a proper bracket, be attached to a floor or other horizontal surface. As shown, the device consists of a ring 22 adapted to encircle the standpipe 1, and having an arm 23 by means of which it is pivotally mounted, as at 24, to a bracket 25 attached to wall 26. An upwardly extending lug 27 carries an adjustable stop 28, by means of which upward rotation of the ring about the pivot 24 is limited, while a downwardly projecting lug 29, carrying stop 30, limits its motion in the opposite direction. A spring 31 between the lug 29 and the face of bracket 25 serves to keep the ring 22 in its upper position, as indicated in Fig. 7^a. Opposite arm 23, ring 22 carries an arm 32, to which is attached the control chain or cable 33. When this form of stop is used, upward motion of the standpipe is arrested by contact of the handle 16 with ring 22. Return of the standpipe is effected by a pull on chain 33, the spring 31 allowing the ring 22 to be depressed sufficiently to throw the valve to release position.

In Figs. 8 and 8^a still another form of stop is shown in which the stop may also function to give a degree of lateral support to the standpipe. In this device, the stop is in the form of an open cage-like member, comprising a bottom ring 34, connected by arms 35 to a sleeve 36 adapted to loosely fit over the pipe 1. The sleeve 36 is attached to the supporting bracket 37 by the parallel forked arms 38, both of which are pivoted to the sleeve and bracket so that motion of the former is substantially parallel to the axis of pipe 1. The clearance between pipe 1 and sleeve 36 is sufficient to allow for the slight lateral movement of the cage member caused by the pivotal movement of arms 38, but any material misalignment of pipe 1 will bring it into contact with the supporting sleeve 36. Bracket 37 is secured in any suitable manner to a wall 39 or other fixed element, and is provided with upper and lower lugs 40 and 41, the former carrying an adjustable stop 42 and the latter a stop 43. A spring 44 around stop 43 serves to hold the ring 34 in its upper position. An arm 45, to which is attached chain 46, provides means for depressing ring 34 to move the valve 15 to release position in a manner already described. While the cage member of which the ring 34 and sleeve 36 form parts has been shown in one piece, necessitating its assembly over the pipe section 1 before the fittings are attached, it will be obvious that this member can be made in halves split along a vertical line, which can be bolted

together in position after the standpipe is assembled.

It is desirable to have the range of vertical movement of the standpipe as great as possible, and in order to do this the standpipe is preferably fitted with a relatively long lifting cylinder capable of moving the nozzle fittings 2 between the extreme positions shown in dotted lines in Fig. 1. The control fitting 3 moves between like positions, and in order to keep the controls at a convenient height when the standpipe is not in use, a rest is provided for holding the standpipe in the intermediate position shown in full lines in Fig. 1, this rest moving to an inoperative position as soon as the standpipe is lifted therefrom.

The rest comprises a plurality of pivotally mounted legs 47 secured to a floor 4 or any equivalent fixed element and preferably symmetrically arranged with respect to the standpipe. Obviously the number of legs employed may be varied. As shown in Figs. 5 and 5^a, each leg 47 is supported by a pivot pin 48 between the spaced legs of a bracket 49, the latter being held in place by any suitable anchoring means, such as bolts 50. The leg 47 has a short lug 47^a extending below the pin 48, and a coil spring 51, retained in the recessed bracket, forces the lever to the position shown in Fig. 5^a, the motion of the lever to a position to the right of that shown being prevented by the stop pin 52. Referring for the moment to Fig. 3, it will be observed that the fitting 3 is provided with a lower flange, larger in diameter than the flange on pipe 1, and that this flange has a circumferential downwardly projecting bead or rim, forming with the pipe flange an annular recess adapted to receive the upper ends of the legs 47 which support the standpipe when it is lowered upon them. It will be obvious that the legs 47 may be readily moved inwardly toward the standpipe by the operator because of the great leverage applied against springs 51, which only have to be strong enough to move the legs to the dotted line position shown in Fig. 1 when the standpipe is lifted.

The discharge from the standpipe nozzles is controlled through hydraulically operated valves located adjacent to the nozzles and to be described in detail later. Each nozzle valve is opened by admitting fluid from the standpipe to the valve operating mechanism through a control pipe 54, the inlet end of which is within the standpipe, and which passes in and out of the fitting 3 through stuffing-boxes 55 to provide an exterior section in which is located the three-way control valve 56. This valve is provided with a manually operable handle 57, by means of which the valve is actuated to either admit fluid to the nozzle valve operating means or to release the fluid from said means

through the vent 58. It will be understood that there are separate control pipes 54, one for each of the nozzles at different floors or elevations, all of the control pipes extending from the control station, and each having a control valve 56 at that station.

In this connection, it is to be noted that the valve 56 is preferably arranged so that the open, neutral and release positions of the handle are the same as the corresponding positions of handle 16 of the standpipe control valve. The nozzle control valves 56 may also be provided with chains by which they may be actuated when in elevated position. Valves 56 are also preferably set closer to the standpipe than valve 15, so that the handles 57 will not be engaged by the stop ring 19, but if it is desired to have one or more of the nozzles automatically shut off when the standpipe reaches a predetermined height, this can be accomplished either by setting the proper valve or valves further from the axis of the standpipe or by making use of extended handles for such valves.

It is highly desirable for the operator to be informed of the conditions obtaining with respect to the discharge from the standpipe nozzles, particularly with reference to the distance to which the extinguishing streams are being thrown from the standpipe. This requires a remote indication as the operator may be several floors removed from the nozzle or nozzles which are in operation and with respect to which an indication is desired. In order to secure this indication, the present invention makes use of the pressure within the standpipe for indicating the length of throw of the streams from the nozzles when they are in any given position, as this factor is dependent upon and will vary with variations in the pressure within the standpipe.

By reference to Fig. 1, it will be apparent that in a vertically movable standpipe of the form illustrated, the distance of throw of the discharge from any nozzle will depend not only upon the pressure obtaining at the nozzle but also upon the height of the nozzle above its particular floor level so that the indication of this factor through the medium of apparatus operated by standpipe pressure will be for a given vertical position of the nozzle. The nozzle position for which the indication is given may be arbitrarily chosen; for example, the reading may be for the throw with the nozzle in its most elevated position, thereby indicating the maximum so obtainable with a given pressure or it may be arranged so that the reading will indicate the throw with the nozzle in its mid position. Obviously in installations where the standpipe is not vertically movable, the pressure factor and the angularity of the nozzles will determine the throw from the nozzle.

In order to secure this indication without resorting to complication in the standpipe

structure, an indication of the pressures obtaining at the nozzles and also the throw therefrom is secured at the operating station by a novel arrangement of indicators located at the operating station and preferably secured in the nozzle control pipes where they are outside the standpipe.

Each nozzle has its indicator remotely located at the operating station, and as shown 10 in Figs. 9 and 10 each indicator preferably comprises a cylindrical casing 59, within which a bourdon tube 60 is mounted, this tube being in communication with the interior of the control pipe upon which the 15 indicator is mounted and operating a pivoted indicator needle 61 through a standard form of linkage, such as used in ordinary pressure gages, which it is not necessary to show. The casing 59 carries a plurality of 20 inwardly extending arms 62 through the inner ends of which the clamping screws 63 pass. The heads of these screws serve to hold in position an annular dial 64, and a circular dial 65, upon one of which is a pressure 25 scale 66 and upon the other of which is a scale 67 indicating the length of the stream thrown by the nozzle. A cover ring 68 serves to hold in place the usual protecting glass face 69.

30 By loosening the screws 63, the dials 64 and 65, and each of them, can be turned to different positions, so that a given actual pressure at the indicator will give readings to show the pressure at or near the corresponding nozzle and/or the length of stream that should be thrown by that nozzle, notwithstanding that the nozzles are at various elevations removed from the central operating station. This feature may be utilized 35 in calibrating the several indicators to show the pressures at the different nozzles, by moving the dials 65 as if to add or subtract from the actual pressures at the several indicators the different static heads between the indicators and the corresponding nozzles and the amounts of pressure loss due to friction or the like in the flow of the water through the standpipe and valves from the region of the indicators to the different nozzles. The 40 graduation of each dial 65 or the position to which it should be set, is determined when the system is installed, and may be determined by calculation or empirically. In like manner the graduations and settings for the several dials 64, showing the throw of the streams from the nozzles corresponding to different pressures, can be determined and these dials fixed in the proper positions.

45 It will be perceived that a distinctive feature of this part of the invention is the provision of indicators responsive to pressure in the standpipe system other than the pressure at the nozzles, in a manner to show the pressures at the respective nozzles and/or the lengths of the streams that should be

thrown. The information thus given is of great advantage in combatting fire with the standpipe. Thus if there is a fire on a given floor of the building, the fireman will operate the proper control valve at the operating station to open the valve of that nozzle and a stream will be delivered and though the man can not see it he can tell by looking at the corresponding indicator what force the stream should have and how far it should carry. If the indication is not satisfactory he can speed up the pump or decrease its speed, or raise or lower the standpipe, or both. If on going out into the street he should find that the stream is not having the effect to be expected from the showing on the indicator, possibly due to some obstruction in the path of the stream, he can again regulate the pump or shift the standpipe vertically or about its axis. If the fire should drop down to a lower floor, it will be necessary to turn on a second nozzle, which will reduce the pressure and the throw of the stream on the floor above, and the fireman will be informed by the indicators of the change in conditions at the first nozzle as well as the force and throw of the stream at the lower floor, and can govern his operations accordingly. The value of the information given by the indicators is not alone 50 in extinguishing a fire at any floor most expeditiously but also in avoiding undue damage to the building and contents by water.

55 If the nozzles are not set at the same angularity in the vertical plane, if for example some of them are horizontal and some of them at predetermined upward deflections, it will be necessary to provide dials 64 having the stream-throw graduations on their scales 67 differently spaced, and to apply to the particular indicator the scale which is graduated for that particular angularity or deflection of nozzle. This is, of course, done when the system is installed.

60 Referring now to Fig. 11, a nozzle assembly is shown in enlarged detail. This comprises the fitting 2 provided with the discharge branch 70, in which is located the angularly disposed valve seat 71 adapted to be controlled by the valve 72. Valve 72 is connected by stem 73 with piston 74, the latter being mounted in cylinder 75 attached to the branch 70. A packing gland 85 prevents escape of fluid from the standpipe to cylinder 75. A spring 86 above piston 74 serves to seat the latter, which is further held to a tight seat by the pressure within the standpipe. Valve 72 is opened from the control station by means of fluid admitted through control pipe 54 to the cylinder 75 below the piston 74, which is larger in diameter than valve 72 and therefore capable of opening the latter against stand pipe pressure. In addition, means for manually opening the valve directly is provided. This 70 75 80 85 90 95 100 105 110 115 120 125 130

means comprises a member clamped to the upper side of piston 74 and having a pair of upstanding spaced arms 76 joined at their upper ends by a web, through which a threaded stem 77 loosely passes, said stem having an enlarged head 78 below said web. The stem 77 screws through the cover plate 79 and carries a hand wheel 80 at its upper end. It will be obvious that the lost motion connection between the wheel 80 and piston 74 permits the valve 72 to be manually opened without interfering with the fluid pressure actuated control, as the valve can be fully opened by fluid admitted below piston 74, when the stem 77 is in the closed position shown in the figure. The end of the discharge branch is preferably threaded as at 81, so that the nozzle 82 may be removably secured thereto by the standard coupling collar 83.

With this form of apparatus, the discharge openings may be used individually in combatting localized fires, either by directing a stream from the nozzle thereon, or by removing the nozzle and attaching a hose carried either on the standpipe or in a suitable rack adjacent thereto and provided with a standard coupling 84 interchangeable with coupling 83.

While the apparatus embodying the several features of the invention has been shown in preferred forms and embodied in a single standpipe, it will be understood that it is intended that the certain features of the invention may be used without the use of others and that apparatus embodying the invention may be applied to forms of standpipes differing from the one shown herein for purposes of illustrating the invention.

It will be understood also that the invention includes all such variations and equivalents as may fall within the scope of the appended claims.

I claim:

1. In apparatus of the class described, the combination of a vertically movable standpipe, fluid pressure actuated means for lifting the standpipe, a manually operable valve mounted to move with the standpipe for controlling said means, and means adapted to close said valve when said standpipe is lifted to a predetermined height.

2. In apparatus of the class described, the combination of a rotary and vertically movable standpipe, fluid pressure actuated means for lifting the standpipe, a manually operable valve mounted to move with the standpipe for controlling said means, and means adapted to close said valve when said standpipe is lifted to a predetermined height in any position of rotation.

3. In apparatus of the class described, the combination with a structure to be protected, of a vertically movable standpipe associated with said structure, fluid pressure actuated means for lifting the standpipe, a manual-

ly operable valve mounted to move with the standpipe for controlling said means, said valve having an operating handle extending outwardly from the standpipe, and means supported by said structure for engaging said handle to close the valve when the standpipe is lifted to a predetermined height.

4. In apparatus of the class described, the combination with a structure to be protected, of a rotary and vertically movable standpipe associated with said structure, fluid pressure actuated means for lifting the standpipe, a manually operable valve mounted to move with the standpipe for controlling said means, said valve having an operating handle extending outwardly from the standpipe, and means supported by said structure comprising a ring encircling the standpipe and spaced therefrom for engaging said handle to close the valve when the standpipe is lifted to a predetermined height in any position of rotation.

5. In apparatus of the class described, the combination with a structure to be protected, of a vertically movable standpipe associated with said structure, fluid pressure actuated means for lifting the standpipe, a manually operable valve mounted to move with the standpipe for controlling said means, said valve having an operating handle extending outwardly from the standpipe and movable downwardly from an open position through an intermediate closed position to a release position, means resiliently supported by said structure for engaging said handle to close the valve when the standpipe is lifted to a predetermined height, and manually operable means for moving said resiliently supported means downwardly to move said valve handle to release position.

6. In apparatus of the class described, the combination with a structure to be protected, of a rotary and vertically movable standpipe associated with said structure, fluid pressure actuated means for lifting the standpipe, a manually operable valve mounted to move with the standpipe for controlling said means, said valve having an operating handle extending outwardly from the standpipe and movable downwardly from an open position through an intermediate closed position to a release position, means resiliently supported by said structure comprising a ring encircling the standpipe and spaced therefrom for engaging said handle to close the valve when the standpipe is lifted to a predetermined height in any position of rotation, and manually operable means for moving said resiliently supported means downwardly to move said valve handle to release position.

7. In apparatus of the class described, the combination with a vertically movable standpipe and means for moving it, of supporting means adapted to engage said standpipe

to hold it in a position intermediate the extreme positions to which it can be moved.

8. In apparatus of the class described, the combination with a standpipe vertically movable between two positions and means for moving it, of pivoted supporting means adapted to be moved into engagement with said standpipe to hold it in a position intermediate said first two positions, and means for automatically moving said supporting means out of engagement with the standpipe when it is lifted above said intermediate position.

9. In apparatus of the class described, the combination with a standpipe vertically movable between two positions and means for moving it, of a rest for holding the standpipe in an intermediate position comprising a plurality of pivoted legs adapted to be manually moved into engagement with the standpipe to support it, means for releasably holding said legs in engagement with the standpipe, and springs acting on said legs to move them out of engagement with the standpipe when the latter is lifted from the supported position.

10. In apparatus of the class described, the combination with a standpipe comprising a pair of flanged pipe sections joined by a flanged control fitting, said standpipe being rotatably and vertically movable, of an extended flange on said fitting forming a downwardly opening annular recess around the standpipe, a pair of supporting legs pivoted at their lower ends and located so that their upper ends are adapted to be moved into said recess in any position of rotation of the standpipe to support the latter in an intermediate vertical position, and means for moving said legs outwardly away from said recess when the standpipe is moved above said intermediate position.

11. In apparatus of the class described, the combination with a standpipe having an operating station and means for supplying fluid under pressure to the standpipe, of a plurality of discharge nozzles located at different elevations other than that of the operating station, and separate means for indicating at the operating station the throw of each of the streams delivered by said nozzles from given positions thereof.

12. In an apparatus of the class described, the combination with a standpipe having an operating station and means for supplying fluid under pressure to the standpipe, of a plurality of discharge nozzles located at different elevations other than that of the operating station, and separate means operated by the pressure of the fluid admitted to the standpipe for indicating at the operating station the throw of each of the streams delivered by said nozzles from given positions thereof.

13. In apparatus of the class described,

the combination with a building having a plurality of floors, of a standpipe having an operating station at one floor, means for supplying fluid under pressure to the standpipe, a plurality of discharge nozzles each located at a different floor, and separate means operated by the pressure of the fluid admitted to the standpipe for indicating at the operating station the throw of the discharge from each of said nozzles with respect to the floor at which it is located when said nozzles are in a given position.

14. In apparatus of the class described, the combination with a standpipe having a central operating station and means for supplying fluid under pressure to the standpipe, of a plurality of discharge nozzles located at different elevations, a plurality of indicators located at the operating station, each of said indicators being connected to the interior of the standpipe and each indicator being calibrated to register the pressure at the elevation of a different nozzle.

15. In apparatus of the class described, the combination with a standpipe comprising a plurality of discharge nozzles at different elevations, valves controlling said nozzles, a central operating station, fluid pressure connections from the interior of the standpipe and extending from the operating station to each of said valves, and manually operable valves at the operating station in each of said connections, of an indicator in each of said connections adjacent to the manually operable valve, each of said indicators having an adjustable dial whereby it may be calibrated to indicate the pressure at the corresponding nozzle.

16. In apparatus of the class described, the combination with a standpipe having an operating station and means for supplying fluid under pressure to the standpipe, of a plurality of discharge nozzles located at different elevations other than that of the operating station, and a set of indicators located at the operating station, said indicators being connected to the interior of the standpipe and each having two dials, one of which is adapted to indicate the pressures at the nozzles and the other of which is adapted to indicate the lengths of the streams thrown from the nozzles.

17. The combination as set out in claim 16, in which each indicator comprises a single movable member responsive to the pressure within the standpipe at the elevation of the indicator, and adjustable dials each of which is adjustable to compensate for the pressure difference in the standpipe between the indicator and the nozzle.

18. The combination of a standpipe system having a central operating station, discharge nozzles at different elevations, means for supplying water to said nozzles, and a plurality of indicators at the central station

responsive to fluid pressure in the supply means of said system other than the pressure at the nozzles, said indicators adapted to indicate pressures at the respective nozzles.

5 19. The combination of a standpipe system having a central operating station, discharge nozzles at different elevations, means for supplying water to said nozzles, and a plurality of indicators at the central station
10 responsive to fluid pressure in the supply means of said system other than the pressure at the nozzles, said indicators having means for indicating both the pressures at the respective nozzles and the respective distances
15 to which streams can be thrown when the nozzles are in operation.

20. In apparatus of the class described, the combination with a standpipe comprising a plurality of discharge nozzles at different
20 elevations, valves controlling said nozzles, a central operating station, fluid pressure connections from the operating station to each of said valves, and manually operable valves at the operating station in each of said connections, of a set of indicators connected with the interior of the standpipe, each of said indicators being adjacent one of said manually operable valves, said indicators being differently calibrated so as to indicate pres-
30 sures at the respective nozzles.
